CONVERSION OF HYDROCARBONS

Harold V. Atwell, White Plains, N. Y., assignor to
Process Management Company, Inc., New York,
N. Y., a corporation of Delaware

Application December 31, 1936, Serial No. 118,539

12 Claims. (Cl. 196—9)

This invention relates to processes for the production of motor fuel by the cracking of relatively heavy hydrocarbon oil and by the conversion of normally gaseous hydrocarbons and more particularly to a combination type of process involving these two general types of operation.

My invention relates in general to the aforementioned type of combination process involving the interconnection of an oil cracking unit, a thermal gas conversion unit, and a catalytic gas polymerization unit. The oil cracking unit is adapted to convert relatively heavy hydrocarbon oil, such as gas oil, to cracked gasoline with normally gaseous hydrocarbons having olefinic constituents as a by-product. The thermal gas conversion unit is adapted to convert normally gaseous hydrocarbons containing both saturated and unsaturated constituents to produce high anti-knock motor fuel while the catalytic gas polymerization unit polymerizes only unsaturated gaseous hydrocarbons as distinguished from the conversion of both saturated and unsaturated gases in the thermal conversion operation. The performance of a thermal gas conversion unit and a catalytic gas polymerization unit is further distinguished by the fact that in the former there is a tendency to produce a liquid product in the motor fuel boiling range having an excess of relatively low boiling components whereas in the latter there is a tendency to give an excess of relatively high boiling liquid polymer. A further distinction between these operations is found in the fact that thermal polymerization effectively converts the lower boiling olefin, e. g., ethylene, to liquid polymers whereas some catalytic operations have practically no effect on this hydrocarbon.

In practising my invention the products of oil cracking are separated by fractionation into motor fuel and normally gaseous hydrocarbons, the motor fuel, for the purpose of explaining my invention, being assumed to have a boiling range of approximately 100 to 400° F. as determined by the A. S. T. M. method for distillation of gasoline. The thus separated normally gaseous hydrocarbons are further fractionated to eliminate hydrogen and methane which can not be economically converted to liquid products. Of the remaining gaseous hydrocarbons, a fraction consisting predominantly of ethylene and ethane is separated and passed to the thermal polymerization unit while the slightly heavier fraction consisting predominantly of C₃ and C₄ hydrocarbons, both sat-

urated and unsaturated, is passed to the catalytic polymerization unit.

Products from the thermal polymerization unit are fractionated in a manner similar to products from the oil cracking unit, this fractionation, particularly with respect to the gaseous product, being effected in the same or separate fractionating systems.

The motor fuel fractions, or part thereof, from the oil cracking and thermal polymerization operations are subjected to further fractionation either separately or in a single fractionating system for the combined products to separate the motor fuel into relatively light, intermediate, and heavy fractions according to boiling point. This fractionation is effected to separate the relatively low boiling constituents which tend to be present in excess in both the thermal polymerized gasoline and in the cracked gasoline. The relatively light and intermediate gasoline fractions, in accordance with my invention, are subjected to repolymerization in order to increase the boiling points thereof, the lightest fraction being passed preferably to the catalytic polymerization zone while the intermediate fraction is preferably passed to the oil cracking zone. When gasoline produced in the oil cracking unit and in the thermal polymerization unit has a boiling range of 100 to 400° F., the separation thereof into the aforementioned fractions may be carried out so that the lower boiling fraction has a boiling range of approximately 100 to 150° F., with the intermediate fraction having a boiling range of approximately 150 to 200° F. Depending upon the product desired, only a portion of either of these fractions need be subjected to repolymerization as described, the balance being diverted for blending in the final product.

By effecting separation in the manner above described, a charging stock of C₃ and C₄ hydrocarbons containing both saturated and unsaturated constituents from the oil cracking and the thermal polymerization units, together with more or less of the normally liquid low boiling constituents of the motor fuel produced from these units, constitutes a charging stock for the catalytic polymerization unit. In the catalytic polymerization unit, the olefins, both normally gaseous and normally liquid, are polymerized to higher boiling products while the paraffinic components of the charge pass through the catalytic unit essentially unchanged. The products from this catalytic polymerization unit are fractionated to recover motor fuel having a boiling range of approximately 100 to 400° F. and a mainly par-

affinic gas consisting predominantly of C₃ and C₄ hydrocarbons which may be passed to the thermal gas conversion unit where they are converted to liquid products mainly in the motor fuel boiling range. The liquid products from the catalytic polymerization unit containing a preponderance of hydrocarbons in the upper part of its boiling range are blended with the heavy fractions of the motor fuel produced by oil cracking and by thermal gas polymerization and with any lighter components of these initial products which are not subjected to repolymerization as described.

For further understanding of my invention, reference will now be made to the accompanying drawing wherein the single figure represents a diagrammatic elevational view of apparatus suitable for carrying out my invention.

Referring to the single figure, hydrocarbon oil, such as a clean gas oil from any suitable source, is passed through line 1 by pump 2 to cracking furnace 3. The cracking furnace 3 may be of the well known construction and the oil in passing therethrough is heated to a temperature of from 350 to 1100° F. while being maintained under a pressure of from 200 to 1000 lbs. per sq. in. to effect the desired cracking thereof into lower boiling hydrocarbons. Preferably the oil is cracked under short time conditions, such as a few seconds, to produce a gasoline of high anti-knock value. If desired, a reaction drum may be used to effect additional cracking of products from the furnace 3 to increase the yield of gasoline. The cracked products from the furnace 3, or a reaction drum, if one is used, are passed through a transfer line 4 having a valve 5 therein to an evaporator 6 which may also be provided with suitable fractionating equipment in the upper part thereof. The evaporator 6 is usually maintained at a lower pressure than that maintained on the oil passing through the furnace 3, as, for example, 50 to 400 lbs. per sq. in. Tar and heavy unvaporized material of the cracked products separated in evaporator 6 are withdrawn therefrom through a line 7 while the vaporous material of the cracked products passes overhead through a line 8 to a fractionating column 9. The fractionating column 9 may be of the well known bubble tower type provided with suitable fractionating trays or plates and separation of the insufficiently cracked products is effected therein. These insufficiently cracked products in the nature of a clean gas oil are withdrawn from the fractionating column 9 through a line 11 and forced by a pump 12 to the inlet of the cracking furnace 3 for reprocessing in the same cycle.

Cracked gasoline and lighter hydrocarbons pass overhead in vaporous form from the fractionator 9 through line 13 and condenser 14 wherein gasoline is condensed to a distillate receiver 15. Normally liquid hydrocarbons having a boiling range of about 100 to 400° F. are separated in the chamber 15 and withdrawn therefrom through line 16, the normally gaseous hydrocarbons, consisting of hydrogen, methane, and the C₂ to C₄ hydrocarbons containing both saturated and unsaturated constituents, being conducted through line 17 to a gas fractionator 18. The normally gaseous constituents passing through line 17 are preferably cooled by any suitable type of heat exchanger 19 prior to entering fractionator 18 to facilitate the desired separation therein. Within the fractionator 18 the normally gaseous hydrocarbons are separated into a fraction containing

mostly C₃ and C₄ hydrocarbons in liquefied condition which is withdrawn through a line 20 and a fraction containing hydrogen, methane, and the C₂ hydrocarbons which is withdrawn through a line 21 and passed through a cooler 22 wherein it is further cooled, optionally with an increase in pressure, by means of a pump not shown, to facilitate separation of hydrogen and methane from the liquefied C₂ fraction in fractionator 23. Hydrogen and methane thus separated may be removed from the system through a line 24 while the remaining C₂ fraction, e. g., ethylene and ethane, is withdrawn through a line 25 and forced by a pump 26 to a thermal polymerization unit. The C₂ fraction passing through the line 25 is admixed with other similar C₂ hydrocarbons or, if desired, hydrocarbons of from two to four carbon atoms per molecule and containing both saturated and unsaturated constituents, introduced through a line 27 by pump 28, and the mixture forced into a thermal polymerization furnace 29. The gaseous hydrocarbons passing through the furnace 29 may be subjected to a temperature of from about 750 to 1100° F. while being maintained under a pressure of from 400 to 3000 lbs. per sq. in. to effect conversion of normally gaseous hydrocarbons into normally liquid products. If desired, the polymerized products from the furnace 29 may be soaked in a soaking drum, not shown, to effect further conversion thereof. The polymerized products, either from the furnace 29 or from the soaking drum if one is used, pass through line 30, cooler 31 wherein they are appropriately cooled, and pressure reduction valve 32 into a fractionating column 33 provided with suitable fractionating trays or plates. If desired, prior or subsequent to pressure reduction on the polymerized products, a suitable quenching medium, such as liquefied gases or normally liquid hydrocarbons, may be intimately contacted with the polymerized products. The polymerized products passing through the fractionating column 33 are therein fractionated to separate material heavier than the desired motor fuel therefrom, this material in the nature of tar and gas oil being withdrawn from the system through a line 34, part or all thereof, if desired, being used as the quenching medium. The motor fuel and lighter hydrocarbon constituents, produced as a result of the thermal polymerization operation, pass overhead from the fractionator 33 through a line 35, condenser 36, and valve 37 to another similar fractionating column 38 wherein separation between the normally liquid hydrocarbons and the normally gaseous hydrocarbons is effected. The normally gaseous hydrocarbons thus separated, containing hydrocarbons of from two to four carbon atoms per molecule and, to some extent, hydrogen and methane, pass through line 39 to line 17 where they join the normally gaseous hydrocarbons resulting from the oil cracking operation. If necessary, a pump, not shown, may be interposed in line 39 for forcing the gaseous products passing therethrough into the line 17. Normally liquid gasoline-like hydrocarbons separated in the fractionator 38 are withdrawn therefrom through line 40 and part or all of this fraction may be conducted through a line 41 to a subsequent fractionating system for separating the motor fuel into certain fractions. Part or all of the motor fuel withdrawn from the chamber 15 through line 16 may be passed through line 42 to the same fractionating system, the motor fuel passing through the lines 41

and 42 being merged and conducted through a line 43 and heat exchanger 44 to a primary fractionating tower 45. Within the fractionating tower 45 a separation of the motor fuel is effected so that a fraction having a boiling range of about 200 to 400° F. is withdrawn therefrom through a line 46 while the lighter fraction passes overhead through a line 47 to another fractionating column 48. A suitable cooler 47' may be interposed in line 47 to cool the products passing therethrough to facilitate the separation being effected in tower 48. The motor fuel entering the fractionator 48 is therein separated into a fraction having a boiling range of about 150° to 200° F. and a lighter fraction, the first mentioned or heavier fraction being withdrawn therefrom through a line 49 and forced by a pump 50 to the oil cracking furnace 3 wherein it is subjected to conditions effective to increase its boiling point by repolymerization and improve its anti-knock. The lighter liquid fraction separated in fractionator 48 passes through line 51 and condenser 52 to separator 53 wherein a normally liquid fraction having a boiling range of from 100 to 150° F. is separated from any gaseous constituents contained in the motor fuel. The gaseous constituents thus separated are removed from the system through line 54 or, if desired, these constituents may be passed to the fractionator 18 to recover hydrocarbons having molecular weight higher than methane therefrom. The lighter liquid fraction from the separator 53 is withdrawn therefrom through a line 55 and forced by pump 56 to a line 58 where it joins the normally gaseous hydrocarbons in liquid form withdrawn from fractionator 18 through line 20. The fraction withdrawn from the fractionator 18 and the lighter normally liquid fraction withdrawn from the separator 53 pass through line 58 to heater 59 wherein they are subjected to a temperature of from 250 to 750° F. while being maintained under a pressure of from about 100 to 1000 lbs. per sq. in. The heated products leaving the heater 59 pass through line 60 to a catalytic reaction chamber 61 having suitable catalysts disposed therein. Any type of catalyst may be used to effect the catalytic polymerization of the unsaturated constituents of the hydrocarbons passing therethrough, such as, for example, phosphoric acid, sulphuric acid, sodium aluminum chloride, and others. Within the catalytic reaction chamber 61 polymerization of the olefins contained in the normally gaseous and normally liquid fractions is effected. While I have shown only one catalytic reaction chamber, it is to be clearly understood that more than one may be used, and if desired an entire battery thereof used, the catalyst in some being revivified while the catalytic polymerization process is being conducted in others. The products of polymerization from the reaction chamber 61 are conducted through line 62 to an evaporator 63, preferably maintained under lower pressure. The evaporator may contain suitable fractionating plates or equivalent fractionating means whereby polymerized products heavier than the desired motor fuel may be separated, these heavier products being withdrawn through line 62'. Unreacted paraffinic gases and liquids, as well as polymerized olefinic constituents of these fluids, pass overhead from the chamber 63 through line 64 and cooler 64' to fractionating column 65. This overhead fraction is fractionated in fractionator 65 to effect separation between the motor fuel

constituents contained therein and lighter, the motor fuel constituents, having a boiling range of 100 to 400° F., being withdrawn through a line 66. Unreacted normally gaseous paraffins separated in the fractionator 65 pass through line 67 and cooler 68 to a separator 69 wherein separation between the C₃ and C₄ paraffins and lighter, if any, is effected, any lighter paraffinic hydrocarbons being withdrawn from the system through a line 71. If desired, the gases passing through line 71 may be conducted to fractionator 18 for further treatment as described. The separated C₃ and C₄ paraffinic hydrocarbons are withdrawn from the separator 69 through a line 72 and forced by a pump 73 to the thermal polymerization furnace 28 wherein they are subjected to polymerization conditions of temperature and pressure to effect conversion thereof into normally liquid hydrocarbons within the motor fuel boiling range. It may not be desirable in some instances to separate all of the motor fuel obtained from cracking hydrocarbon oil and that obtained from the thermal polymerization of the gases into various fractions for repolymerization. In accordance with this aspect of my invention, part or all of the motor fuel withdrawn from separator 18 through line 16 may be conducted through line 14, and part or all of the motor fuel withdrawn from fractionator 38 through line 40 may be conducted through line 75, to a manifold 77 wherein the motor fuels are blended. Moreover, the fraction of the motor fuel boiling between 200 and 400° F. and separated in fractionator 45 may be passed through the line 48 to the manifold 77 for blending with the aforementioned motor fuels. Furthermore, if it is not desired to repolymerize all of the fraction boiling between 150 and 200° F. and withdrawn from the fractionator 48 through line 49, a part thereof may be passed through line 78 to manifold 77 for blending with the fraction having a boiling range between 200° and 400° F., and similarly a part of the fraction having a boiling range of between 100 and 150° F., and withdrawn from the separator 53 through line 55, may be passed through line 78 for admixture with the motor fuel constituents passing therethrough.

As a modification of my invention, part of the C₃ to C₄ normally gaseous hydrocarbons withdrawn from fractionator 18 and passing through line 20 may be by-passed through line 82 for admixture with part or all of the relatively light normally liquid fraction passing through line 56 to extension line 81. The mixed C₃ and C₄ hydrocarbons and the lighter normally liquid hydrocarbons, in accordance with this modification, may be passed through line 83 to the thermal polymerization furnace 28 wherein they may be subjected to thermal polymerization in admixture with the C₂ fraction and other normally gaseous hydrocarbons being processed therein.

Separate fractionators have been shown for effecting the desired separation of the hydrocarbons in various stages of the process to enable a ready understanding of this invention. It is to be understood, however, that fewer fractionators may be provided and the same results accomplished. For example, a single fractionator may be provided in lieu of fractionators 33 and 38 or fractionators 45 and 48. Each of the various fractionators may be provided with suitable refluxing medium introduced in a well known manner as well as cooling coils in the top and heating coils in the bottom thereof, if desired. More-

over, instead of fractionating the gaseous hydrocarbons as described, an absorption system, well understood, may be used instead of the fractionators 18 and 23.

5 Obviously, many modifications of my invention may be made without departing from the spirit and scope thereof as appearing hereinafter in the appended claims.

I claim:

- 10 1. In the manufacture of normally liquid hydrocarbons from normally gaseous hydrocarbons, the process that comprises separating normally gaseous hydrocarbons containing saturated and unsaturated constituents into a fraction predominating in C_2 hydrocarbons and another fraction predominating in higher boiling normally gaseous hydrocarbons, separately subjecting each of said fractions to conversion conditions to convert at least some of the normally gaseous hydrocarbons to normally liquid gasoline-like hydrocarbons, separating low-boiling normally liquid constituents boiling below about 200° F. from said normally liquid gasoline-like hydrocarbons, and admixing low-boiling normally liquid constituents thus separated with at least one of the normally gaseous fractions undergoing conversion.
- 20 2. In the manufacture of normally liquid hydrocarbons from normally gaseous hydrocarbons, the process that comprises separating normally gaseous hydrocarbons containing saturated and unsaturated constituents into a fraction predominating in C_2 hydrocarbons and another fraction predominating in higher boiling normally gaseous hydrocarbons, separately subjecting each of said fractions to conversion conditions to convert at least some of the normally gaseous hydrocarbons to normally liquid gasoline-like hydrocarbons, separating the normally liquid gasoline-like hydrocarbons from the products resulting from the conversion of said normally gaseous fractions, separating low-boiling normally liquid constituents boiling below about 200° F. from said normally liquid gasoline-like hydrocarbons, and admixing low-boiling normally liquid constituents thus separated with at least one of the normally gaseous fractions undergoing conversion.
- 30 3. In the manufacture of normally liquid hydrocarbons from normally gaseous hydrocarbons, the process that comprises separating normally gaseous hydrocarbons containing saturated and unsaturated constituents into a fraction predominating in C_2 hydrocarbons and another fraction predominating in higher boiling normally gaseous hydrocarbons, separately subjecting each of said fractions to conversion conditions to convert at least some of the normally gaseous hydrocarbons to normally liquid gasoline-like hydrocarbons, fractionating the products resulting from the conversion of the fraction predominating in C_2 hydrocarbons to separate therefrom low-boiling normally liquid constituents boiling below about 200° F., and admixing low-boiling normally liquid constituents thus separated with at least one of the normally gaseous fractions undergoing conversion.
- 40 4. In the manufacture of normally liquid hydrocarbons from normally gaseous hydrocarbons, the process which comprises separating gaseous hydrocarbons containing saturated and unsaturated constituents into a fraction predominating in C_2 hydrocarbons and another fraction predominating in higher boiling normally gaseous hydrocarbons, subjecting the fraction predominating in C_2 hydrocarbons to thermal conversion

conditions to effect conversion of normally gaseous hydrocarbons to normally liquid gasoline-like hydrocarbons, subjecting the fraction predominating in higher boiling normally gaseous hydrocarbons to catalytic conversion conditions to effect conversion of normally gaseous hydrocarbons to normally liquid gasoline-like hydrocarbons, separating from the products of said thermal conversion low-boiling normally liquid constituents boiling below about 200° F., admixing low-boiling normally liquid constituents thus separated with the gaseous fraction undergoing catalytic conversion treatment, separating from the products of said catalytic conversion unconverted normally gaseous paraffinic hydrocarbons and admixing said paraffinic hydrocarbons with said fraction undergoing thermal conversion.

5. The method of producing gasoline motor fuel which comprises subjecting normally liquid hydrocarbons higher boiling than gasoline to cracking conditions of temperature and pressure to effect conversion thereof to gasoline-like hydrocarbons and normally gaseous hydrocarbons, subjecting normally gaseous hydrocarbons thus produced having more than one carbon atom per molecule to polymerizing conditions of temperature and pressure to effect conversion thereof to gasoline-like hydrocarbons, separating from gasoline-like hydrocarbons thus produced a light gasoline fraction containing in substantial proportion the normally liquid light ends of gasoline and an intermediate gasoline fraction higher boiling than said light gasoline fraction and substantially free of the heavy ends of gasoline, admixing said light gasoline fraction with said normally gaseous hydrocarbons undergoing polymerizing treatment, and admixing said intermediate gasoline fraction with said normally liquid hydrocarbons undergoing cracking treatment.

6. The method in accordance with claim 5 wherein said light gasoline fraction is recovered at least in part from the products of said cracking treatment.

7. The method in accordance with claim 5 wherein said light gasoline fraction is recovered at least in part from the products of said polymerizing treatment.

8. The method in accordance with claim 5 wherein said polymerizing treatment is carried out under thermal conditions in the absence of catalytic material.

9. The method in accordance with claim 5 wherein said polymerizing treatment is carried out in the presence of a polymerizing catalyst.

10. The method of producing gasoline motor fuel which comprises subjecting normally liquid hydrocarbons higher boiling than gasoline to cracking conditions of temperature and pressure to effect conversion thereof to gasoline-like hydrocarbons and normally gaseous hydrocarbons, separating from said normally gaseous hydrocarbons a fraction predominating in C_2 hydrocarbons and a fraction predominating in higher boiling normally gaseous hydrocarbons, separately subjecting each of said fractions to polymerizing conditions to convert at least a portion thereof to gasoline-like hydrocarbons, separating from the products of said cracking treatment a light gasoline fraction containing in substantial proportion the normally liquid light ends of gasoline, and admixing said light gasoline fraction with said C_2 fraction undergoing polymerizing treatment.

11. The method of producing gasoline motor fuel which comprises subjecting normally liquid

hydrocarbons higher boiling than gasoline to cracking conditions of temperature and pressure to effect conversion thereof to gasoline-like hydrocarbons and normally gaseous hydrocarbons, 5 separating from said normally gaseous hydrocarbons a fraction predominating in C₂ hydrocarbons and a fraction predominating in higher boiling normally gaseous hydrocarbons, separately subjecting each of said fractions to polymerizing 10 conditions to convert at least a portion thereof to gasoline-like hydrocarbons, separating from the products of said cracking treatment a light gasoline fraction containing in substantial proportion the normally liquid light ends of gasoline, and admixing said light gasoline fraction with said higher boiling normally gaseous hydrocarbon fraction undergoing polymerizing treatment. 15

12. The method of producing gasoline motor

fuel which comprises separating normally gaseous hydrocarbons into a fraction predominating in C₂ hydrocarbons and a higher boiling fraction, subjecting said C₂ fraction to elevated conditions of temperature and pressure to effect conversion thereof to gasoline-like hydrocarbons, separately subjecting said higher boiling normally gaseous fraction to polymerizing conditions of temperature and pressure in the presence of a polymerizing catalyst to effect conversion thereof into gasoline-like hydrocarbons, separating from the products of the thermal conversion treatment of said C₂ fraction a light gasoline fraction containing in substantial proportion the normally liquid light ends of gasoline, and admixing said light gasoline fraction with said higher boiling normally gaseous fraction undergoing catalytic polymerizing treatment. 10 15

HAROLD V. ATWELL.
